DESIGN FOR A CLOCK CASING

Paul G. Darrot, Southbury, Conn., assignor to
General Time Instruments Corporation, New
York, N. Y., a corporation of Delaware

Application March 16, 1938, Serial No. 75,866

Term of patent 3½ years

To all whom it may concern:

Be it known that I, Paul G. Darrot, a citizen
of the Republic of France, residing in the city
of Southbury, in the county of New Haven and
State of Connecticut, have invented a new, orig-
inal, and ornamental Design for a Clock Casing,
of which the following is a specification, refer-
ence being had to the accompanying drawing,
forming a part thereof.

Fig. 1 is a front view of a clock casing show-
ing my new design.

Fig. 2 is a side view of my clock casing.

Fig. 3 is a top view of my clock casing.

I claim:

The ornamental design for a clock casing, as
shown.

PAUL G. DARROT.
